SAFETY RAZOR

Georges Monnet, Washington, D. C.

Application December 27, 1943, Serial No. 515,728

6 Claims. (Cl. 30—70)

This invention relates to razors and refers more particularly to safety razors which do not have to be taken apart and reassembled in the course of their use.

Safety razors now on the market consist usually of at least three pieces which have to be taken apart and reassembled whenever it is necessary to insert a razor blade or remove it from the razor.

So called "one-piece razors" now in use are comparatively complicated and easily breakable, and cannot be used satisfactorily with two edge blades.

An object of the present invention is the provision of a one-piece safety razor which is simple in construction and effective in operation.

Another object is the provision of a safety razor which does not have to be taken apart or reassembled for the purpose of inserting a razor blade therein or for removing that blade, and which is simple and sturdy in construction and effective in operation.

A further object is the provision of a one-piece safety razor, which is so constructed, that the blade supporting surface may be conveniently exposed for the purpose of placing a blade thereon, whereupon the blade is clamped between this surface and a cover.

Other objects of the present invention will become apparent in the course of the following specification:

In accomplishing the objects of the present invention, it was found desirable to provide a blade support which is rotatably mounted upon a handle and which cooperates with a cover movable in relation to the blade support upon guides which may constitute a part of the handle and/or of the blade support.

The clamping of the blade between the blade support and the cover may be attained through the use of a screw thread engagement between the cover and a portion of the handle.

The invention will appear more clearly from the following detailed description when taken in connection with the accompanying drawings showing by way of example, preferred embodiments of the inventive idea.

In the drawings:

Figure 1 shows, in side elevation, a safety razor constructed in accordance with the principles of the present invention.

Figure 2 is an end elevation of the safety razor shown in Figure 1.

Figure 3 is a top view of the razor.

Figure 4 shows the blade support carrying a blade.

Figure 5 is a section along the line 5—5 of Figure 3.

Figure 6 shows, in side elevation, the head of a somewhat differently constructed razor.

5 Figure 7 is a section through the head shown in Figure 6.

Figure 8 is a top view of the head shown in Figures 6 and 7.

Figure 9 is a section along the line 9—9 of Figure 7, with the blade support extending at right angles.

Figure 10 is a side elevation of a differently constructed razor.

Figure 11 is an end view of the razor shown in Figure 10.

Figure 12 is an end view of the razor head in its inoperative position.

Figure 13 is a section along the line 13—13 of Figure 10.

20 The safety razors shown in the drawings may be made of metal, wood, plastics, or any other suitable material.

The razor shown in the Figures 1 to 5, has a handle 20 which may be of any suitable shape, 25 and which has an upper neck portion 21 carrying a pivot 22.

The lower end of the pivot 22 is firmly embedded in the neck portion 21. The pivot 22 carries a flange 23. The upper end 24 of the 30 pivot 22 is provided with screw threads.

The blade support consists preferably of two parts in order to facilitate assembly around the flange 23. The two parts may be of substantially the same form in order to simplify manufacture.

35 The lower part 25 is pivotally mounted upon the pin 22 and rests upon the upper end of the neck portion 21.

Central recesses formed in the supporting part 25 receive the lower part of the flange 23 and the 40 adjacent portion of the pivot 22. The support 25 has curved lower surfaces and a flat upper surface which is engaged by a corresponding surface of the upper support portion 26. The support portion 26 has central recesses receiving the upper part of the flange 23 and the adjacent end of the pivot 22. The two support portions 25 and 26 are connected with each other and may rotate upon the pivot 22.

The upper surface 27 of the support 26 may 45 carry projections 28 and 29 fitting into the central slot 30 of a razor blade 31. The threaded end 24 of the pivot 22 is so dimensioned that it extends conveniently through the same central opening 30 of the blade.

55 The pivot end 24 and the projections 28 and

29 serve as guides for receiving the razor blade 31 and for preventing excessive side movement of the blade when it lies upon the surface 27 of the support 26.

The cover of the razor head has a portion 32 which clamps the blade in the operative position of the razor.

For that purpose, the cover portion 32 is provided with a central threaded hole 33 which is adapted to receive the end 24 of the pivot 22. The cover portion 32 may be provided with a projecting portion 34 containing the hole 33.

The cover portion 32 is carried by two supports 35 and 36 which are movable within recesses 37 and 38 provided in the support portions 25 and 26 at the ends thereof.

The supports 35 and 36 are joined by a yoke 39 having a middle ring portion 40 embracing the neck portion 21 of the handle 20. The supports 35 and 36 and the yoke 39 are comparatively narrow and may be conveniently grasped by the fingers of the user for the purpose of manipulating the cover 32.

In the operative position of the razor, the blade 31 lies upon the surface 27 of the support 26 with the guides 28 and 29 and the pivot 22 extending through the central opening 30 of the blade 31. The pivot end 24 is screwed into the hole 33 and the blade is firmly clamped between the support 26 and the cover 32.

In order to remove the blade, the user turns the handle 20 until the pivot end 24 is withdrawn from the threaded hole 33. Then, the cover 32 may be raised upwardly with the supports 35 and 36 sliding in the grooves 37 and 38 and the ring 40 moving upon the neck portion 21.

The friction of the supports 35 and 36 in the grooves 37 and 38 should be sufficiently great to maintain the cover 32 in the raised position. Then, the blade 31 may be conveniently lifted off the guides 28 and 29 and the pivot end 24 and may be conveniently replaced by a new one.

The razor shown in Figures 6 to 9 includes a handle having a neck portion 21 which carries a pivot 50. The pivot 50 carries an inner flange 51 and is provided with a threaded outer end 52.

A lower support portion 53 is rotatably mounted upon the pivot 50 and is firmly connected with the upper support portion 54.

The two support portions 53 and 54 are joined by bolts 55 and 56 which are screwed into bore holes provided in the support portions 53 and 54.

The bolt heads 57 and 58 extend above the blade supporting surface 59 and serve as guides adapted to receive the razor blade 31. The blade 31 is clamped between the supporting surface 59 and a cover 60 provided with a central projection 61 receiving a threaded hole 62.

The cover 60 has openings 63 and 64 receiving the bolt heads 57 and 58 in the operative clamping position of the razor. The cover 60 is connected with two supports 65 and 66 extending at a distance from the support members 53 and 54 and joined by a yoke 67, the middle portion of which has an opening through which the pivot 50 extends.

As indicated in Figure 8, the cover portion 60 with the supports 65 and 66 and the yoke 67 may be conveniently rotated in relation to the supporting members 53 and 54, or the supporting members 53 and 54 may be rotated in relation to the cover 60.

When the cover 63 extends substantially at right angles to the supporting members 53 and 54, a blade 31 may be conveniently placed upon

the supporting surface 59 of the member 54 with the pivot end 52 and the bolt heads 57 and 58 extending through the central opening of the blade. Then, the cover 60 may be swung back into its position directly above the blade, whereupon the cover is moved downwardly and the pivot end 52 is screwed into the bore hole 62. The bolt heads 57 and 58 will be introduced then into the openings 63 and 64 of the cover 60. In this construction the relative swinging movement between the cover 60 and the supporting members, facilitates the removal and the insertion of the blade.

The safety razor shown in Figures 10 to 13 has a handle 70 provided with an upper cylindrical portion 71 which may be narrower than the handle 70 and which contains two grooves 72 and 73 disposed on opposite sides thereof. These grooves contain the disks 74 and 75 respectively, which can slide and turn in the grooves. The disk 74 is connected to a transverse bar 76, while a similar bar 77 is attached to the disk 75.

The cover 78 of the razor carries downwardly extending brackets 79 and 80 which are connected with the bars 76 and 77. The brackets 79 and 80 are located at a distance from the two supporting members 81 and 82.

The handle 70 carries a pivot 83 which is firmly mounted thereon and which carries a flange 84. The pivot 83 has a threaded end 85.

The lower supporting member 81 has a recess receiving a part of the flange 84. Another part of the flange is contained in a recess of the upper supporting member 82. The two members 81 and 82 are firmly connected with each other and are mounted upon the pivot 83.

The cover 78 contains a threaded bore hole located within the projection portion 86 and adapted to receive the threaded end 85 of the pivot 83.

The inoperative position of the razor is illustrated in Figure 12. In this position, the cover 78 is located below the support 82 so that a safety blade 31 may be conveniently placed upon the support 82. Then, the cover 78 may be swung back into the position shown in full lines in Figure 11, whereupon the end 85 may be screwed into the bore hole in the projection 86, thereby firmly clamping the blade 31 between the cover 78 and the support 82.

It is apparent that the illustrations shown above have been given by way of illustration and not by way of limitation and that the articles above described are subject to wide variation and modification without departing from the scope or intent of the present invention. All such variations and modifications are to be included within the scope of the present invention.

What is claimed is:

1. A safety razor, comprising a handle, an upper supporting member having an upper curved surface for a razor blade and a lower substantially flat surface, a lower supporting member having a lower curved surface and an upper substantially flat surface engaging the flat surface of the upper supporting member, means connecting the flat surfaces of the supporting members, a pin having one end firmly connected with said handle, a flange connected with said pin and located in recesses formed in said supporting members, whereby said supporting members are rotatably mounted upon said pin, and a covering member adapted to cover said blade, said covering member being connected to said handle and having a threaded hole formed therein, the other end

of said pin being threaded and being screwed into said hole in the clamping position of said razor.

2. A safety razor, comprising a handle, a supporting member for a razor blade, a pin having one end firmly connected with said handle, said supporting member being rotatably mounted upon said pin intermediate its ends, and a covering member adapted to cover said blade, said covering member having a threaded hole formed therein, the other end of said pin being threaded and being screwed into said hole in the clamping position of said razor, arms connected with said covering member on opposite sides thereof and extending on opposite sides of said supporting member and a yoke connected with said arms and having a central portion embracing said handle.

3. A safety razor, comprising a handle, a supporting member for a razor blade, a pin having one end firmly connected with said handle, said supporting member being rotatably mounted upon said pin intermediate its ends, and a covering member adapted to cover said blade, said covering member having a threaded hole formed therein, the other end of said pin being threaded and being screwed into said hole in the clamping position of said razor; arms connected with said covering member on opposite sides thereof and extending on opposite sides of said supporting member and within parallel grooves formed in said sides of the supporting member, and a yoke connected with said arms and having a central portion embracing said handle.

4. A safety razor, comprising a handle, a supporting member for a razor blade, a pin having one end firmly connected with said handle, said supporting member being rotatably mounted upon said pin intermediate its ends a covering member adapted to cover said blade, said covering member having a threaded hole formed therein, the other end of said pin being threaded and being screwed into said hole in the clamping position of said razor; arms connected with said covering member on opposite sides thereof and extending on opposite sides of said supporting member and

at a distance therefrom, and a yoke connected with said arms and having a central portion embracing said handle.

5. A safety razor, comprising a handle, an upper supporting member having an upper curved surface for a razor blade and a lower substantially flat surface, a lower supporting member having a lower curved surface, and an upper substantially flat surface engaging the flat surface of the upper supporting member, screws interconnecting said supporting members and having heads projecting from the blade supporting surface, and adapted to extend through a central opening of a blade, a pin having one end firmly connected with said handle, said supporting members being rotatably mounted upon said pin intermediate its ends, a covering member adapted to cover said blade, said covering member having a threaded hole formed therein, the other end of said pin being threaded and being screwed into said hole in the clamping position of said razor, said covering member having other openings formed therein, and receiving the heads of said screws, in the clamping position of the razor; arms connected with said covering member on opposite sides thereof and extending on opposite sides of said supporting member, and at a distance therefrom, and a yoke connected with said arms and having a central portion embracing said handle.

6. A safety razor, comprising a handle, a supporting member for a razor blade, a pin having one end firmly connected with said handle, said supporting member being rotatably mounted upon said pin intermediate its ends, a covering member adapted to cover said blade, said covering member having a threaded hole formed therein, the other end of said pin being threaded and being screwed into said hole in the clamping position of said razor; arms connected with said covering member on opposite sides thereof and extending on opposite sides of said supporting member and bars connected with said arms and slidably and swingably mounted in grooves formed in said handle on opposite sides thereof.

GEORGES MONNET.
